UNITED STATES PATENT OFFICE

2,663,755

SHEATHED ELECTRIC CONDUCTOR

John V. McBride, Lebanon, Conn., assignor to
 The Plastic Wire & Cable Corporation, Jewett
 City, Conn., a corporation of Connecticut

Application September 28, 1949, Serial No. 118,260

4 Claims. (Cl. 174—117)

1

This invention relates to sheathed electric conductors and an object is to provide an improved construction of insulated electric conductor for general purposes which can be installed substantially anywhere. Rural electrification installations, for example, are particularly severe and require a cable which is well insulated electrically, is well protected against mechanical injury and against moisture, acids, alkalis, oil, fungus, weather and sunlight and yet can be easily handled and readily bent to facilitate installation. In such installations it is also frequently necessary for the cable to withstand considerable tension, such, for example, as when the cable is required to span considerable distances without intervening supports, or when it is jerked and pulled around corners and through holes during installation. This calls for a cable having sufficient tensile strength to provide a greater margin of safety than is usually found in a cable which is also constructed to have the desired flexibility. Also, although cables have heretofore been provided with tension resistant cords or the like, they have been unsatisfactory because subject to rotting, or fungus growth, or objectionable for other reasons.

A feature of this invention is the provision of an electric cable having the necessary rugged insulation for prolonged service of the above type, constructed and arranged to be so flexible as to permit ready installation thereof in and around sharp corners or wherever considerable bending of the cable is required, and which also has a greatly improved form of stress resisting means.

A further feature of the invention is the provision in an insulated electric cable of a strong tension resisting member formed of an inorganic, non-conducting material which is not subject to rotting, fungus growth and other objectionable features common to strands of the type usually employed in cable insulation such as cotton, jute or the like. The tension member is such as to provide maximum strength with minimum size, so that no increase in the overall dimensions of the cable envelope is produced.

A further feature is the provision of a multi-conductor electric cable in which each individual conductor is slidably relatively to the insulating envelope. This feature contributes to the remarkable flexibility of the product permitting the cable to be bent as easily in the plane common to both conductors as in a direction at right angles thereto.

These and other objects and advantageous fea-

2

tures are accomplished by the present invention.

In the accompanying drawings:

Figure 1 is a perspective view of a multi-conductor cable constructed in accordance with one embodiment of this invention.

Fig. 2 is a similar view of another embodiment.

Figs. 3 and 4 are sectional views of the cable shown in Figs. 1 and 2, respectively.

Fig. 5 is an elevation illustrating the easy flexibility of a cable constructed in accordance with the present invention.

Although the drawings illustrate different modifications of the invention incorporated in a two-conductor cable, it will be apparent that the invention is equally applicable to single conductor cables as well as to cables having more than two conductors, if desired.

In the form of the invention shown in Fig. 2 the electric conductors 11a, 12a are each surrounded by an individual insulating sheath 21, preferably of the same material as the outer envelope 22, such as vinyl chloride or a co-polymer. Each sheath 21 is surrounded by a protective, reinforcing and insulating layer of stress resisting strand 23 and the two conductors with their respective sheaths and stress resisting layers are enclosed in a substantially flat envelope 22, which also is preferably of vinyl chloride or a co-polymer.

In order to avoid deterioration of the stress resisting strand due to rotting, fungus growth and other causes of deterioration heretofore encountered, I form the strand of inorganic, non-conducting material, preferably of fiber glass.

Such material provides the necessary strength and flexibility with a minimum size of strand so that the outside dimension of the insulating envelope is not increased by the presence of the strand. This is of especial advantage in a flat cable having a substantially flat envelope, as no increase in the outside dimension of the envelope is required. Fiber glass also has the advantage of being a good electrical insulator so that the presence of the strand does not decrease the insulation provided by the envelope between the electric conductors.

In this embodiment, each conductor is first supplied with the extruded sheath 21 by running through a suitable extruding die. Then the layer of stress resisting fiber glass is applied around each sheath, and such covered wires and sheaths are then fed through a suitable extruding machine to have the envelope 22 applied thereto.

In this embodiment of the invention it will be found that each conductor and its surrounding

sheath is slideable relatively to the outer envelope 22, the intervening layer of fiber glass reducing the friction between each sheath and the surrounding envelope, so that this form of cable is as easily flexible in the plane of the conductors as in any other plane as is clear from Fig. 5. With the fiber glass surrounding the conductors as in this form of the invention, the insulating envelope is also reinforced against clamping pressures as might be encountered in fastening the cable in position, and against serious deformation due to high pressures at elevated temperatures.

As illustrated in Figs. 2 and 4, the conductors 11b, 12b are enclosed in separate sheaths 25 similar to the sheaths 21 each sheath having an identifying or indicating characteristic, such, for example as a distinctive contrasting color. The color of one sheath may be the same as the envelope 26 as long as the other sheath is of a contrasting color. In this embodiment a stress resisting cord 16b of fiber glass is employed and extends longitudinally of the cable parallel to the conductors and, as illustrated, is substantially midway between them.

It will be seen that the present invention provides an electric cable which can be used in practically any type of installation, which will easily absorb the tensile stresses imposed on it and yet which is so flexible as to permit ready installation around sharp corners and the like.

Although the drawing shows the invention applied to cable having solid conductors, it will be understood that the invention is equally well adapted to cables having any other form of conductor, stranded or otherwise.

The invention can be variously modified and adapted and portions of the improvements can be used without others.

I claim:

1. An electric cable of indefinite length comprising parallel conductors, an extruded insulating envelope of homogeneous flexible thermoplastic material slideably encircling and enclosing said conductors whereby to facilitate flexing of the cable in the plane of said conductors, said envelope forming a solid mass between said conductors extending for the full width of said conductors, and stress resisting means extending longitudinally through said envelope comprising a layer of fiber glass surrounding each of said conductors within said envelope and enclosed thereby.

2. An electric cable of indefinite length comprising parallel conductors, an extruded, flexible insulating sheath of homogeneous thermoplastic material enclosing each conductor, an extruded, flexible insulating envelope of homogeneous thermoplastic material encircling and slideably engaging and enclosing each of said sheaths, said envelope being free of interconnection with said sheaths whereby to facilitate flexing of the cable in the plane of said conductors and said envelope.

providing a large mass of insulation extending between said sheaths for the full width of the sheathed conductors, and a stress resisting member of fiber glass material enclosed within said envelope and extending longitudinally through said mass of insulation parallel to said conductors.

3. An electric cable of indefinite length comprising parallel conductors, an extruded, flexible insulating sheath of homogeneous vinyl chloride enclosing each conductor, an extruded, flexible insulating envelope of homogeneous vinyl chloride encircling and enclosing each of said sheaths and being slideable thereover, said envelope being free of any interconnection with said sheaths and providing a large mass of insulation extending between said sheaths for the full width of the sheathed conductors, whereby to facilitate sliding of the envelope on the sheaths incident to the flexing of the cable in the plane of said conductors, and a stress resisting member of fiber glass enclosed within said envelope and extending longitudinally therethrough.

4. An electric cable of indefinite length comprising parallel conductors, an extruded, flexible sheath of homogeneous vinyl chloride enclosing each conductor, a layer of inorganic non-conducting stress resisting fiber glass surrounding each sheath, and an extruded, flexible envelope of homogeneous vinyl chloride surrounding and slideably engaging and enclosing each of said fiber glass layers, whereby to facilitate flexing of the cable in the plane of said conductors, said envelope forming a solid mass between said sheaths for the full width of the sheathed conductors to maintain said conductors in predetermined spaced relation.

JOHN V. McBRIDE.
